UNITED STATES PATENT OFFICE

143,797

DESIGN FOR WALLPAPER

M. Magdalene C. Couts, Dayton, Ohio

Application September 6, 1945, Serial No. 121,894

Term of patent 7 years

(Cl. D59—10)

To all whom it may concern:

Be it known that I, M. Magdalene C. Couts, a citizen of the United States, residing at Dayton, in the county of Montgomery and State of Ohio, have invented a new, original, and ornamental Design for Wallpaper, of which the following is a specification, reference being had to the accompanying drawings, forming part thereof.

In the drawings:

I claim:

The ornamental design for wallpaper, as shown.

M. MAGDALENE C. COUTS.
